UNITED STATES PATENT OFFICE.

ERNST SCHALL, OF HARTFORD, CONNECTICUT.

DESIGN FOR A SPOON.

SPECIFICATION forming part of Design No. 20,704, dated April 28, 1891.

Application filed April 6, 1891. Serial No. 387,882. Term of patent 3½ years.

To all whom it may concern:

Be it known that I, ERNST SCHALL, a citizen of the United States, residing at Hartford, in the county of Hartford and State of Connecticut, have invented and produced a new and original Design for Spoons, Forks, and the Like, of which the following is a specification, reference being had to the accompanying drawings, forming a part thereof.

10 The figure in the drawing is a plan view of a spoon showing my design.

In the accompanying fac-simile drawing, the letter *a* denotes the handle of a spoon, *b* the shank, and *c* the bowl, constructed, as shown, of somewhat irregular outline. The spoon bears the pictorial representation of the familiar episode in the life of Israel Putnam, in which, when escaping from British troops, he rides down "Horseneck" pass on horseback.

15 20 The picture shows a man on horseback riding down a steep and rugged incline, near the top

of which a number of mounted men are halted as if pausing in a close pursuit of the first. The surrounding scenery is that of a country region on a somewhat precipitous hillside— 25 rough, broken, and clothed with trees and underbrush.

Spaces are left on appropriate parts of the article for the reception of dates, names, or other inscriptions. 30

I claim as my invention—

The design for a spoon or the like article of table-ware, herein shown and described, the same comprising the handle part and the bowl portion and having depicted thereon the pictorial representation of the historical event of Putnam riding down Horseneck, as set forth. 35

ERNST SCHALL.
